(57) CLAIM

The ornamental design for a table, as shown and described.

DESCRIPTION

FIG. 1 is a perspective view of an embodiment of a table showing my new design;

FIG. 2 is a top view thereof;

FIG. 3 is a front elevation view thereof; and,

FIG. 4 is a left side elevational view (right side elevational view is a mirror image thereof).

The broken lines are for environmental purposes only and form no part of the claimed design.

1 Claim, 3 Drawing Sheets

FIG. 2
